No. 713,522.

Patented Nov. 11, 1902.

W. R. W., H. E. M. & D. J. L. STEINER.

DEVICE FOR DETACHING AND REMOVING HORSES FROM THEIR STALLS
IN CASE OF FIRE.

(Application filed July 10, 1902.)

(No Model.)

UNITED STATES PATENT OFFICE.

WILLIAM R. W. STEINER, HERMAN E. M. STEINER, AND DANIEL J. L. STEINER, OF BRADDOCK, PENNSYLVANIA.

DEVICE FOR DETACHING AND REMOVING HORSES FROM THEIR STALLS IN CASE OF FIRE.

SPECIFICATION forming part of Letters Patent No. 713,522, dated November 11, 1902.

Application filed July 10, 1902. Serial No. 115,095. (No model.)

To all whom it may concern:

Be it known that we, WILLIAM R. W. STEINER, HERMAN E. M. STEINER, and DANIEL J. L. STEINER, citizens of the United States 5 of America, residing at Braddock, in the county of Allegheny and State of Pennsylvania, have invented certain new and useful Improvements in Devices for Detaching and 10 Removing Horses from their Stalls in Case of Fire, of which the following is a specification, reference being had therein to the accompanying drawings.

This invention relates to certain new and 15 useful improvements in devices for detaching and removing horses from stalls in case of fire, and has for its object the provision of novel means whereby the halter-strap may be easily detached and the horse or other animal forced out of the stall in case of the 20 conflagration of the stable.

Another object of the present invention is to provide novel means that will extend through the stable-wall and may be easily 25 operated from the outside without the necessity of entering the stable.

The invention further aims to provide a device of this character that shall be extremely 30 simple in construction, strong, durable, comparatively inexpensive to manufacture, and highly efficient in its use; furthermore, one 35 that will permit of any number of stalls being operated at the same time, if desired.

With the above and other objects in view the invention consists in the novel construction, combination, and arrangement of parts 40 to be hereinafter more fully described, and specifically pointed out in the claims.

In describing the invention in detail reference is had to the accompanying drawings, 45 forming a part of this specification, and wherein like numerals of reference indicate like parts throughout the several views, in which—

Figure 1 is a longitudinal sectional view of a portion of the stable. Fig. 2 is an enlarged 45 vertical sectional view of the pipe having arranged therein the operating-shaft and horse-detacher. Fig. 3 is a perspective view, partly in section, of one of the guides arranged in each side of the stall, in which an endless 50 sprocket-chain and shaft operate. Fig. 4 is

a perspective view, partly in longitudinal section, of the pipe, showing more particularly the means of connection between the operating-shaft and pipe, whereby both are turned in unison. Fig. 5 is a view in perspective of 55 a portion of the chain and the ejecting-rod secured thereto.

In the drawings, 1 represents the longitudinal sectional view of a portion of the stable, and 2 one of the stalls. 3 indicates the manager. In the sides of the stalls are formed recesses, in which are secured sprocket-wheels 4 4, and at the rear of the stalls, in the sides thereof, are secured similar sprocket-wheels 5 5, which are secured upon the shafts 6. 60 These sprocket-wheels 4 and 5 engage endless sprocket-chains 7 7, having connected thereto a rod 8, which is normally in close proximity to the sprocket-wheels 4 4 and which extends transversely across the stalls. These 70 sprocket-chains 7 and also the rod 8 operate in guideways 9, formed in the guides 10, secured in the sides of the stalls. These guides preferably carry flanges having openings 11 formed therein to receive fastening means. 75 The sprocket-wheels 4 are rigidly secured upon the hollow shaft 12, which is likewise secured in the sides of the stalls, extending transversely across the stall and through the stable to the outside thereof. This hollow 80 shaft 12 has formed therein an opening 14 and has arranged therein a shaft 15, said shaft being rotatably mounted in a bearing 16, secured in the hollow shaft. This shaft 15 also has secured thereon an adjustable 85 sleeve 17, having a set-screw 18 and carrying an extension 19, upon which is secured the ring or snap-hook 20 of the halter-strap 21. On the outer end of the hollow shaft 12 is secured a ratchet-wheel 22, which when operated 90 engages the pawl 23, secured in any suitable manner upon the side of the building, said pawl engaging the ratchet-wheel. The hollow shaft 12 also carries a bracket at its outer end, which is designated by the numeral 24, said bracket carrying a bearing 25, formed integral therewith, and within said bearing is pivotally mounted a crank-handle 27, the inner end of the crank-handle being 95 pivotally secured, as at 28, to the outer end 100

of the shaft 15. The outer end of the bracket 24 has formed integral therewith a U-shaped bracket 26.

The operation of our improved device is as follows: In case of a conflagration the crank-handle 27 is pressed inwardly toward the building, thus withdrawing the shaft 15, which carries the sleeved collar 17, in turn carrying the extension 19, which when pulled outwardly releases the ring 20, allowing the horse to be forcibly ejected from the stall, which is accomplished in the following manner: The crank-handle having been thrown inwardly toward the building, the same engages in the U-shaped bracket 26, whereby the same is temporarily locked. When the operator rotates the crank-arm, the hollow shaft 12 will be rotated at the same time, thus rotating the sprocket-wheels 4 and 5, carrying the chains 7, to which is secured the rod 8, which in turn ejects the horse from the stall. We provide the ratchet-wheel 22 and the pawl 23 to prevent the rearward rotation of the hollow shaft 12, which would be caused by the horse again trying to enter the stall and forcing the bar 8 forward.

Heretofore great difficulty has been experienced in saving horses' lives in a burning stable, as the natural inclination of the animal is to rush into the flames instead of away from the threatening danger, and it is thought that our present invention overcomes such difficulties and provides a device that will not endanger the lives of the person or persons operating the same.

The many other advantages obtained by the use of our improved device will be readily apparent from the foregoing description, taken in connection with the accompanying drawings.

It will be noted that various changes may be made in the details of construction without departing from the general spirit of our invention.

Having fully described our invention, what we claim as new, and desire to secure by Letters Patent, is—

1. In a horse detacher and ejector, the combination of a stall, fastening means, means

arranged in said stall to automatically release the said fastening means, sprocket-wheels, endless chains passing over said sprocket-wheels, means to operate said wheels, and means carried by said chains to eject the animal, substantially as described.

2. In a horse detacher and ejector, the combination of a stall, a hollow shaft secured to said stall, a shaft secured in said hollow shaft, means to operate said shafts independently and in unison, attaching means extending through said hollow shaft, sprocket-wheels carried by said hollow shaft, sprocket-wheels arranged in the rear of said stall, endless chains passing over said sprocket-wheels, and a rod connecting said sprocket-chains, substantially as described.

3. In a device of the character described, the combination of a stall, guides secured in the sides of the stall, a hollow shaft secured to said stall, a shaft secured in said hollow shaft, means to operate said shafts independently and in unison, attaching means extending through said hollow shaft, a ratchet-wheel secured to the said hollow shaft, a pawl, sprocket-wheels carried by said hollow shaft, sprocket-wheels arranged in the rear of the said stall, endless chains passing over the said sprocket-wheels, and a rod connecting said sprocket-chains, substantially as described.

4. In a device of the type set forth, the combination with the stall, of a rotatable transversely-arranged hollow shaft, a fastening means for securing the horse in the stall, means arranged in the said shaft for releasing the said fastening means, means for rotating the said shaft, and means for forcing the horse out of the stall, said last-named means being operated simultaneously with the rotation of the said shaft, substantially as described.

In testimony whereof we affix our signatures in the presence of two witnesses.

WILLIAM R. W. STEINER.

HERMAN E. M. STEINER.

DANIEL J. L. STEINER.
